DESIGN FOR A DRESS

Jacob M. Sterngold, New York, N. Y.

Application April 13, 1939, Serial No. 84,248

Term of patent 3½ years

To all whom it may concern:

Be it known that I, Jacob M. Sterngold, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the specific dress disclosed of the specific appliquéd around the neck portion of the dress as shown.

I claim:

The ornamental design for a dress, substantially as shown and described.

JACOB M. STERNGOLD.
